CLAIM

What is claimed is the ornamental design for a display screen with graphical user interface, as shown and described.

DESCRIPTION

FIG. 1 is a front view of a display screen design with a graphical highlight user interface, showing a first embodiment of the new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof;

FIG. 9 is a front view of a ninth embodiment thereof; and,

FIG. 10 is a front view of a tenth embodiment thereof.

The broken lines in the drawings depict portions of the display screen design that form no part of the corresponding embodiment of the claimed design.
